UNITED STATES PATENT OFFICE

PETER WEISSWASSER, OF DETROIT, MICHIGAN

MOP CABINET

Application filed May 4, 1932. Serial No. 609,291.

The object of my invention is to provide a small, closed wall cabinet for inclosing and hanging a hand mop, for concealing the fabric section which ordinarily presents an offending appearance.

Another object is to produce a mop cabinet that will inclose and retain a wet mop, and is provided with a heat drying unit mounted therein for drying the fabric section.

A further object is to produce a mop cabinet that is ornamental in appearance suitable for hanging in an occupied room, that is simple in construction, easily and efficiently operated and that can be manufactured at a very low cost. These several objects are attained in the preferred form by the construction and arrangement of parts more fully hereinafter set forth.

Similar parts on all drawings are marked by similar numerals or letters.

Fig. 1 is a front view of the cabinet showing the exterior of the cabinet and the air perforations formed therein.

Fig. 2 is a side view of the cabinet showing the electric connection of the heating unit as mounted within the cabinet.

Fig. 3 is a top view of the cabinet showing the cabinet support, and the hinge construction of the front panel.

Fig. 4 is a bottom view of the cabinet showing the open bottom and deflected back wall.

Fig. 5 is a vertical sectional view taken on the line 5—5 of Fig. 1 showing the electric heating unit and the interior arrangement of the cabinet.

Fig. 6 is also a vertical sectional view taken on the same line 5—5 of Fig. 1 where the electric heater unit is omitted and replaced by a rod support.

Fig. 7 is also a vertical sectional view taken on the same section line 5—5 of Fig. 1 showing an alternate cabinet structure, where the mop is inserted within the cabinet top instead of at the bottom as shown in the former cases.

Fig. 8 is a top view of the cover used on the alternate form shown in Fig. 7 show-

ing the spring mop support mounted thereon.

In general, my device comprises a small metal box structure of perforated walls, open at the bottom, and is provided with a removable front panel. A small tubular heating unit is mounted crosswise of the cabinet over which the mop fabric may be hung. The cabinet is provided with suitable supports for hanging same on any wall hook or nail, so that the cabinet may be retained in a vertical position.

I will now describe more fully the detailed construction of my device referring to the drawings and the marks thereon.

The cabinet —A— is made of thin, light sheet metal, preferably cut from a single sheet and formed into a rectangular box shaped structure comprising the back —1—, side walls —2— and top —3—, the metal sheet being folded to leave the front and bottom of the cabinet open. A small tab section —4— may be cut from the top —3— and folded parallel to the back —1—, said tab being formed with a small hole —5— therethrough provides means for hanging the cabinet on any suitable wall hook or nail as may be placed along a vertical wall. The bottom section —a— of the back —1— is deflected into the cabinet inclosure to prevent any water or moisture as may gather within the cabinet from coming in contact with the supporting wall surface. Both of the side walls —2— are provided with perforations —b— to allow free circulation of air through the cabinet inclosure at all times for aiding in drying the mop fabric. A panel cover —6— formed with side bars —c— and with a top hinge hook —d— is fitted over the front cabinet opening, and is supported thereon by the hinge hook —d— engaging the hinge rod —7— fixedly mounted through the top of the side walls —2— near the front edges thereof, completely inclosing the cabinet chamber except for the narrow opening —c— at the bottom. The cover panel —6— is also provided with the perforations —b— to increase the air circulation through the cabinet box.

Crosswise of the cabinet —A—, between

100

the side walls —2—, and preferably above the cabinet center, is fixedly mounted an electric heating unit —8—, suitable for connecting in any electric lighting circuit by the terminal wires —9— and —10—. The type and structure of the electric unit —8— is not material, as any standard tubular heater will operate, the purpose being solely for drying the mop fabric —f—.

10 In using my mop cabinet after proper installation on a suitable wall support, the cover —6— is removed from the cabinet section and the flexible mop section —f— is hung over the tubular heating unit —8— as indicated in the Fig. 5 of the drawings, the mop handle —g— being allowed to hang downward through the bottom cabinet opening —e—. The cover —6— may then be replaced over the cabinet front as heretofore described and the electric heating unit turned on. Any water as may be dripping from the mop fabric is prevented from coming in contact with the supporting wall upon which the cabinet is hung, because of 20 the deflected back section —a—. When the mop is sufficiently dried the electric current may be turned off the heater. The circulation of air through the cabinet wall perforations —b— also tend to dry the fabric.

25 When desired, and for producing a less expensive cabinet, the heating unit —8— may be omitted or replaced by a rod support —12— as shown in the Fig. 6 of the drawings. With this construction the mop fabric —f— is allowed to dry by air circulation only.

An alternate form of cabinet is shown in the Figs. 7 and 8 of the drawings, comprising a similar cabinet structure as heretofore described, except the front panel —6a—, back —1a— and sides —2a— are all formed from one sheet section into a rigid inclosure, and with the top —3a— hinged to the front wall —6a— by the hinge pin —13— mounted therethrough, the top —3a— being designed to turn back on the hinge support and to allow the mop section to be inserted within the cabinet from the top instead of in the front as heretofore shown and described, the mop being held in position therein by a spring hanger —14— mounted on the cover —3a—, and which engages the mop handle —g— when the cover is closed there-

on as shown in Figs. 7 and 8 of the drawings. The mop may also be supported by any other suitable means desired, such as wall hooks or nails suitable for engaging with the handle section. The cabinet may 70 also be provided with the tubular heating unit —8— or with a support rod —12— as may be desired. The operation is the same as heretofore described.

It is apparent that my device is subject 75 to various modifications in both design and mechanical details without departing from the spirit of my invention, and I claim the cabinet as illustrated and in any other form that is substantially a substitution of parts 80 herein shown.

Having fully described my mop cabinet, what I claim as my invention and desire to secure by Letters Patent is:

1. A mop cabinet adapted for retaining 85 and drying a hand mop head therein, comprising a small rectangular cabinet inclosure formed with an open bottom end and having cabinet back wall at the lower end deflected within the cabinet bottom opening, 90 both side and front walls being formed with perforations therethrough, said cabinet being provided with a hinged top wall recessed for allowing a mop handle to be passed therethrough, a spring handle support mounted on said top wall capable of engaging and supporting the mop handle and attached mop head, an electric heating unit mounted within the cabinet inclosure positioned to contact the mop head for drying same.

2. A mop cabinet adapted for retaining 105 and drying a hand mop head therein, comprising a small rectangular cabinet inclosure formed with an open bottom end and having the cabinet back wall deflected within the cabinet bottom opening, both the side and front walls being perforated, means mounted on said cabinet walls for attaching same to any suitable wall hook, said cabinet being 110 also provided with a hinged top wall formed with a recess opening therein for receiving a mop handle therethrough, a spring handle support mounted on the top hinged wall adapted to engage and support a mop handle 115 and attached mop head when the mop head is placed within the cabinet.

PETER WEISSWASSER.
